SAUCER

William A. Coughlin, Lansdowne, Pa.

Application January 27, 1954, Serial No. 28,697

Term of patent 14 years

(Cl. D44—9)

FIG. 2.

FIG. 1.

FIG. 3.

To all whom it may concern:

Be it known that I, William A. Coughlin, a citizen of the United States, residing in Lansdowne, Delaware County, Pennsylvania, has invented a new, original, and ornamental Design for a Saucer, of which the following is a specification, reference being had to the accompanying drawing, forming part thereof, in which:

Fig. 1 is a view in perspective of a saucer showing my new design;

Fig. 2 is a top plan view of the saucer on an enlarged scale, and

Fig. 3 is a cross-sectional view of the saucer on the line 3—3, Fig. 2.

I claim:

The ornamental design for a saucer, substantially as shown.
